UNITED STATES PATENT OFFICE

JOSEPH LASHENICK, OF BROOKLYN, NEW YORK

ADVERTISING DISPLAY APPARATUS

Application filed August 4, 1928. Serial No. 297,484.

This invention relates to advertising devices, and has among its objects the production of an inexpensive sign in which advertising matter upon a moving band or film may be displayed in continuous series and illuminated by sunlight or natural light to produce an effect similar to that resulting from the employment of artificial light.

Other, further, and more specific objects of this invention will become readily apparent to persons skilled in the art from a consideration of the following description when taken in conjunction with the accompanying drawings wherein:

Fig. 1 is a perspective view of my device, showing the appearance of the characters on the film at the top of the device and the reflected images appearing in front of the device.

Fig. 2 is a vertical cross-section of the apparatus shown in Fig. 1.

Fig. 3 is a cross-section along the line 3—3 of Fig. 2 viewed in the direction of the arrows.

Fig. 4 is a cross-sectional view illustrating a modification of the construction shown in Fig. 1, wherein provision is made for extra rollers so as to permit the employment of bands or films of increased length.

Referring to Figs. 1, 2 and 3, the apparatus comprises a casing or cabinet 1 having the top window 2 and the exhibiting front window 3. A mirror 4 is positioned within said casing in angular relationship, preferably at 45°, to the top and front windows of the casing. A plurality of rollers 5 are supported within this casing and over these rollers an endless band or film 6 is trained. The arrangement of the rollers 5 within the casing is preferably such that the film may be readily removed by sliding longitudinally from said rollers.

This band or film 6 is preferably made of celluloid and cemented at the ends to form an endless sheet, and the body of this band or film is either entirely impervious to light rays or is less pervious than the designs or lettering thereon. However, if desired the body of the band may be the portion having greater permeability to light rays than the

lettering or designs. By either of these arrangements, as light is passed through the top window an image of the lettering or design on this band will be reflected from the mirror 4 through the front exhibiting window 3.

The rollers 5 are driven by a suitable form of motive power such as a clock or electric motor, but I prefer to use an electric motor 7 which is connected to one of the rollers 5 by means of a belt 8. As these rollers revolve, the band 6 is moved endlessly past the top window 2 and a continuous display of the advertising matter on this film is exhibited through the front window 3.

In order to maintain the band or film 6 in a smooth condition and to prevent sagging and distortion, I provide the transparent supporting member 9. I prefer to make this supporting member 9 of glass which has high transmissive power for sunlight and this glass of any coloration may be employed to meet the needs and fancies of the users. The supporting member 9 serves to keep in smooth horizontal position the portion of the film passing the window 2. Also, in order to maintain the film in taut condition throughout its entire length, I have provided the roller 10 which bears against the side 11 of the film 6 and which is disposed at one end of the pivoted arm 12. This roller 10 is brought into and out of engagement with the film 6 by means of the bolt 13 and nut 14. I preferably use a spring 15 to connect the rod 13 to the arm 12 as this permits the roller 10 to yield whenever the portion of the film at which the ends are joined passes over this roller 10, thus affording smooth passage of the film while the taut condition is maintained.

The rollers 5 revolve about shafts supported by any suitable framework 16 which are connected to the body of the casing 1. The arrangement of rollers should be such as to admit of the free passage of the film past the top window 1, and in the construction shown in Fig. 2 the film passes by the top window 2 down one side of the mirror then below the mirror and up the other side of the mirror.

In the modified construction shown in Fig. 4, I have provided additional rollers 5^a, which permit the use of films of greater length than in the construction shown in Fig. 2. The number of these extra rollers may be increased to meet the particular needs and requirements since these extra rollers 5^a and the part of the film trained about these rollers are beyond the mirror and the exhibiting portion of the apparatus.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

20 I claim as my invention:

1. In an advertising display apparatus, a casing having a compartment at each end and a middle compartment with a top window, a front exhibiting window and an inner mirror angularly disposed to and facing said windows, rollers within each end compartment, an endless band with advertising matter thereon trained over said top window and over the rollers disposed in each of the end compartments, means for effecting movement of said band over said rollers and adjacent to the top window, said arrangement of band, mirror and windows constituting means for allowing natural light to pass through the upper window and be reflected by said mirror through the front window and thereby display a replica of the advertising matter on said band in said front window.

40 2. In an advertising display apparatus, a casing having a compartment at each end and a middle compartment with a top window, a front exhibiting window and an inner mirror angularly disposed to and facing said windows, rollers within each end compartment, an endless band with advertising matter thereon trained over the rollers disposed in each of the end compartments and passing through the walls of said middle compartment adjacent to the top window and above said mirror and also passing through the end walls of said middle compartment and below said mirror, a transparent supporting member disposed immediately beneath the path of travel of said band near the top window for supporting said band in smooth horizontal position, and means for maintaining said band in taut condition while moving over said rollers.

65 In testimony whereof I affix my signature.
JOSEPH LASHENICK.
